D 16194

UNITED STATES PATENT OFFICE.

JAMES H. ALEXANDER, OF PHILADELPHIA, PENNSYLVANIA, ASSIGNOR TO
THOMAS DEVLIN & CO., OF SAME PLACE.

DESIGN FOR A PLATE FOR CARRIAGE-STEPS.

SPECIFICATION forming part of Design No. 16,194, dated August 11, 1885.

Application filed June 8, 1885. Term of patent 14 years.

To all whom it may concern:

Be it known that I, JAMES H. ALEXANDER, a citizen of the United States, residing at Philadelphia, in the county of Philadelphia and State of Pennsylvania, have invented a certain new and useful Design for Step-Plates for Carriages, &c.; and I do hereby declare the following to be a full, clear, and exact description of the invention, reference being had to the accompanying drawing, which forms part of this specification, in which the figure is a plan of the same.

This invention has relation to designs for the step-plates of carriages; and said design consists of four touching circles, each inclosing a six-pointed star, the rays of each star being composed of two oppositely curved lines, and the points of said rays being connected by curved lines of the same radius as the rays, as hereinafter more specifically described and claimed.

A represents the plate, having the ogee edge *a*. Within this edge the surface of the plate is ornamented by the production upon it in relief of four circles, B B, each of which includes a six-pointed star, C, in relief, each of the rays of said stars being composed of two oppositely curved radial lines, *c c'*, joined at both their ends, and the rays being connected to each other at their outward extremities by curved relief-lines *c' c*', which are segments of

circles of the same radii as the circles B B. The circles B B touch each other, and as a result there are three stars for each pair of circles, the upper two circles constituting one pair and the lower two another pair, there being thus six stars on the plate. The central curvilinear diamond-shaped space, D, is occupied by a symbol or letter. The spaces between the two curved lines which form each ray, as well as those between the tips of the rays, the latter being bounded by the circles and the lines *c c'*, form ovaliform cells *d d'*, while the spaces between one ray and another (shown at *e e'*) are curvilinearly triangular in contour, and these latter open all the way through the plate.

What I claim as my invention is—

A design for carriage-step plates, consisting of four touching circles each inclosing a six-pointed star, the rays of each star being composed of two oppositely curved lines, and the points of said rays being connected by curved lines of the same radius as the rays, substantially as shown and described.

In testimony that I claim the foregoing I have hereunto set my hand this 18th day of May, 1885.

JAMES H. ALEXANDER.

Witnesses:

WILL H. POWELL,
R. DALE SPARHAWK.

DEPARTMENT OF THE INTERIOR,
UNITED STATES PATENT OFFICE,
WASHINGTON, D. C., *August 18, 1885.*

Whereas Messrs. Connolly & Bros., attorneys for the parties in interest, have, in writing, refused to receive Letters Patent No. 16,194, granted August 11, 1885, upon the application of James H. Alexander, of Philadelphia, Pennsylvania, for a "Design for Plate for Carriage-Steps," for the reason that the drawing attached thereto is not that pertaining to nor allowed in the case, and—

Whereas an examination shows that said Letters Patent were not issued in accordance with the official record of the case,

*It is hereby ordered that the seal of said Letters Patent be broken, the grant returned to the file marked *canceled*, and that Letters Patent, in proper form, be issued pursuant to the record of the case in the Patent Office.*

M. V. MONTGOMERY,
Commissioner of Patents.

Approved:

H. L. MULDROW,
First Assistant Secretary of the Interior.
